CONVEYER

Horton Conrad, Chicago, Ill., assignor, by mesne assignments, to Lake Shore Engineering Company, Iron Mountain, Mich., a corporation of Michigan

Application October 24, 1944, Serial No. 560,105

11 Claims. (Cl. 198—203)

1

This invention relates in general to a conveyor and is more particularly described as a portable conveyor for receiving coal or other material and discharging it at a distance therefrom. In unloading coal or other material from a wagon or truck, it is frequently desirable to discharge material at a different elevation either above or below the point where it was received. For power conveyors, an electric motor or an internal combustion engine may be provided, but a source of current is not always available, and for a more general use or application, a small internal combustion engine is desirable. If such an engine is placed upon a conveyor which is tilted at various inclinations, the oiling and fuel systems are seriously affected if not rendered inoperative. The present invention provides an adjustable mounting for a conveyor of this type in which provision is made for maintaining the engine in upright position for various inclinations in either direction from a horizontal position.

An important object of the invention is in the provision of a conveyor adapted to be positioned at various inclinations and having an adjustable motor support and mounting which may be varied in accordance with the inclination of the conveyor to maintain an upright position and thus to provide for an efficient operation of the engine.

A further object of the invention is to provide a portable conveyor of a type adapted to be carried with a truck and transported from place to place for use therewith, the conveyor having a wheel upon which it is mounted and a removable engine and mounting which may be quickly applied to and removed from the conveyor.

A still further object of the invention is to provide a belt type conveyor having a gear reduction drive from an operating engine or pulley and a conveyor belt which may be tightened and loosened depending upon the material or service desired.

A still further object of the invention is to provide a light and strong portable conveyor adapted to receive material at one end and to deliver it from the other end with an intermediate driving means mounted above the conveyor and movable at various angles with respect thereto.

Other objects of the invention will appear in the specification and will be apparent from the accompanying drawing in which,

Fig. 1 is a side elevation of a conveyor in accordance with this invention.

2

Fig. 2 is a sectional view of the conveyor shown in Fig. 1; and

Fig. 3 is a sectional detail taken on the line 3—3 of Fig. 2.

5 This invention is particularly designed and intended to be carried with coal trucks and is used for this and other material handling operations. The conveyor is positioned so that the rear or receiving end is located close to the 10 end or side of a truck where material may be shoveled or dumped directly upon the receiving end of the conveyor, the other end of the conveyor is elevated or inclined to deliver the material at a higher or lower level and the operating engine is set up in its holder and fastened at such an angle that it will be held therein in substantially upright position regardless of the inclination of the conveyor.

Referring now more particularly to the drawings, a conveyor frame is preferably composed of light-weight angle and channel bars 6 and 7 to form an elongated hollow structure of the desired length. The frame is substantially rectangular in cross section and comprises a metal trough or plate 8 extending along the top and having upright sides 9 with upwardly inclined ledges 10 and downwardly turned edges 11 which overlap the upper edges of the side frames. This trough 8 extends to a position adjacent the rear 15 end of the conveyor and is continuous to the front or discharge end of the conveyor.

At the rear end of the conveyor is a loading section 12 which is flush at the top with the remainder of the conveyor but preferably has 20 continuous side plates and a bottom 13 which is inclined upwardly toward the end so that by disposing wheels 14 upon an axle 15 which is mounted in brackets 16 extending downwardly from the main frame of the conveyor at a point 25 just beyond the loading section, the rear end may approach the ground upon which the wheels are supported, thereby allowing the other or discharge end to be elevated to a greater extent.

Movable upon the plate or trough 8 is a continuous belt 17 which passes over a roller or pulley 18 mounted upon brackets 19 extending forwardly from the end of the frame and also mounted at the rear end upon an adjustable pulley or roller 20 which has a mounting shaft 21 engaged at each end by a screw 22 which passes through a fixed perforated ear 23 projecting outwardly at the side of the frame and having adjusting nuts 24 for moving the pulley, thereby tightening the belt and holding the pulley in any adjusted position. The side plates

of the rear section are formed with slots 26 through which the ends of the shaft 21 project which guide the rear pulley in its tightening or loosening movement.

Overlying the adjustable pulley is a guard plate 25 which extends from the top of the conveyor at the rear downwardly at its inner end to closely overlie the belt so that material discharge upon the belt at this end is protected from engagement with the mounting pulley 20.

Connected to the front pulley is a gear 28 having a sprocket chain 29 connecting it to a small sprocket 30 carried on a counter shaft 31 mounted in brackets 32 attached to the outer upright sides 9 of the trough 8. Connected at the other end of the shaft 31 is a large sprocket 33 having a sprocket chain 34 connecting it to a small sprocket 35 carried by a counter shaft 36 mounted in other brackets 37 secured to the outer upright sides 9 of the trough 8. This forms a reduction drive for a belt which is connected to an operating motor or engine.

Attached to the side frames of the conveyor and extending upwardly therefrom adjacent the longitudinal center are engine mounting plates 40 each having a central mounting notch 41 in the upper edge and one of the plates having a projection 42 extending inwardly therefrom.

An internal combustion engine 43 for driving the conveyor belt is mounted upon a base 44 secured at opposite sides to end plates 45 and 46. The end plate 45 has a mounting stud 47 adapted to be seated in one of the notches 41 of one of the mounting plates 40 and at the other end, a motor shaft 48 extends beyond the end plate 46 and is seated in the notch 41 of the other mounting plate 40 and has a driving pulley 49 secured to the shaft outside of the mounting plates. This driving pulley is connected by a belt 50 with a driving pulley 51 mounted on counter shaft 36 of the reduction drive and since the driving pulley 49 is usually smaller than the pulley 51, it constitutes a further reduction drive connection. Since the engine 43 should always be operated in an upright position and the conveyor may be inclined either upwardly or downwardly, the motor mounting allows the base 44 to swing with its plates 45 and 46 upon the stud 47 and the shaft 48 respectively in the notches of the mounting plates 40 thereby maintaining the pulley 49 always upon the same center line and requiring no change for any adjusted inclination of the motor mounting. In order to hold the motor in different angular positions, the side plate 46 is provided at its lower edge with a plurality of notches 52 preferably arranged upon a curved arc with the shaft 48 as a center. These notches are adapted to engage the stud 42 extending inwardly from the adjacent mounting plate 40 depending upon the inclination of the conveyor, and also in the horizontal position thereof, the arrangement being such that in applying the motor mounting to the conveyor in any inclined position, the motor mounting is held with the engine in its proper upright position as it is lowered into engagement with the slots 41 and as the slots 41 are engaged, the corresponding notch 52 will be engaged with the stud 42 in accordance with the inclination of the conveyor.

In order to maintain the driving belt 50 tightly in driving position, an idler pulley 53 is mounted at the end of a lever 54 upon a pivot 55 carried by the adjacent mounting plate 40 and having a long extending arm 56 which constitutes a

weight for holding the pulley in belt distending position.

Also mounted near the rear end of the conveyor in side plates 57 secured to the upright sides 5 of the trough is an idler pulley 58 for engaging the belt 11 and guiding it to the rear roller 20. With this construction, the conveyor is readily set up for use, the motor and its mounting may be quickly removed and quickly applied to the conveyor by simply disengaging or engaging the driving belt 50 which is tightened to driving relation and held in that position by the belt tightener pulley 53, and the motor mounting, which is easily removable by simply lifting it from engagement with the notches 41 of the supporting plates 40, is as easily returned and set in any inclined position with respect to the conveyor for keeping the engine in upright position by simply lowering the engine mounting in the notches 41 until one of the positioning notches 52 engages the angle positioning stud 42 whereupon the motor mounting is also properly seated in the notches 41.

This conveyor is of a light and strong construction such that it is adapted to be carried with the truck or other vehicle and may be moved upon its wheels 14 therewith, and may also be easily set in place and supported by the wheels in any desired position, the outer or discharge end being usually engaged or held in place to maintain the conveyor at its desired level as, for example, upon a window ledge 60, as shown in Fig. 1, or any other suitable supporting structure either above or below its level position. Material to be conveyed is deposited upon the moving belt at the rear end of the conveyor and is moved and discharged from the belt over the pulley 18 at the other end of the conveyor. The reduction drive makes it possible to use a relatively small high speed engine which will move the material rapidly upon the conveyor.

I claim:

1. In a conveyor, the combination with a longitudinal hollow frame, of an endless belt movable on end pulleys therein, an engine and mounting means therefor carried by the frame intermediate the ends of the belt, an engine support pivotally carried in the mounting, driving means extending from the engine which is mounted on the support to one of the end pulleys, and interengaging means between the support and the mounting for positively adjusting and holding the engine at different angular positions in the mounting to keep the engine in upright position independent of the inclination of the conveyor.

2. A portable conveyor, comprising a wheel mounted frame with an endless conveyor belt mounted for movement longitudinally thereof, an internal combustion engine for driving the belt, and a mounting on the frame including a carrier in which the engine is adjustable angularly about its shaft as a horizontal fixed driving axis, the adjustment comprising a pin fixed on the mounting, and the carrier comprising an upright plate having notches in the edge to engage the pin so that the engine may be held in upright position for different inclined angular positions of the conveyor.

3. A portable conveyor, comprising a hollow frame, an endless belt mounted for movement therein, an engine mounting connected to and extending upwardly from the frame, an internal combustion engine and a carrier therefor rotatably engageable in the mounting about the engine shaft as an axis, a reduction drive connection from the engine shaft and mounted in the

frame for moving the belt, and an adjustable connection between the engine carrier and the engine mounting comprising a pin fixed on the mounting and an upright plate on the carrier having a plurality of notches at the lower edge to engage the pin for holding the engine at different angular positions in the mounting but still maintaining the belt driving connection.

4. In a conveyor, the combination with an endless belt mounted in a longitudinal hollow frame, of a pair of side plates each having an open notch at the upper end, an internal combustion engine and a carrier therefor mounted in the notches of the side plates and including an engine shaft and a driving pulley extending outwardly through the notch in one side plate with the driving pulley at the outer side thereof, a reduction drive connection between the pulley and one end of the belt, and means including a projection at the inner side of one of the side plates, and a plate projecting downwardly from the engine carrier with notches in the lower edge thereof for selected engagement with the projection for holding the engine in upright position when the conveyor is horizontal or inclined in either direction therefrom, and maintaining the driving connection between the engine and the belt for all inclined positions of the conveyor.

5. A motor mounting for a belt conveyor movable longitudinally in a hollow frame, the mounting comprising side plates each extending upwardly from the frame having an open notch at the upper end, a motor carrier having extremities for mounting it to swing in the notches of the plates, one of the extremities comprising a driving shaft from the motor and a driving pulley at the outer end of the shaft outside of the plate, a driving connection extending from the pulley for operating the belt, a projection extending inwardly from one of the plates, a positioning plate extending downwardly from the carrier having a plurality of notches in the lower edge any one of which is adapted to engage the projection when the carrier is seated in the notches of the side plates to hold the motor carrier in an upright position, the notch of the positioning plate which is engaged depending upon the inclination of the conveyor.

6. A portable conveyor, comprising a wheel mounted frame adjustable to different inclinations on the wheels, a trough extending in the conveyor along the top thereof and having upwardly extending edges which overlap and are secured to the upper sides of the frame, an endless belt having its upper run extending in the trough and its lower run extending below the trough, a driving pulley for mounting the belt at the forward end thereof, an adjustable pulley for mounting the belt at the rear end of the frame, an engine mounting intermediate the ends of the frame, an engine carrier rotatably adjustable in the mounting upon a horizontal axis for various degrees of inclination of the frame, means for connecting the carrier to the mounting at different angles, and a speed reducing drive connection between the engine in the mounting and the pulley at the forward end of the belt which is maintained for all relative angular positions of the engine with respect to the frame.

7. In a portable conveyor, a frame having a wheeled support upon which it may be variably inclined and an open trough at the top thereof, a belt having its top run in the trough and its

bottom run below the trough, a driving pulley at the front end of the conveyor over which the belt passes, and a rear adjustable pulley in the frame at the other end of the belt movable for varying the belt tension, an engine mounting in the frame intermediate the ends of the belt, an engine supported by the mounting above the frame having a driving connection mounted in the frame for engaging the pulley at the front end of the belt, and a guard plate at the rear end of the conveyor overlying the adjustable pulley therein for insuring the deposit of material on the belt and for protecting the pulley at the end thereof.

15 8. In a conveyor, a hollow metallic frame having a wheeled mounting upon which it may be variably inclined and an open trough in the upper side of the frame with sides engaging over the upper edges of the frame, an endless belt having its upper run located in the bottom of the trough, a driving pulley and means for mounting it in extended position at the front end of the conveyor, a tightening pulley adjustably mounted at the rear end of the frame over which the belt passes, an idler pulley mounted in the frame below the trough near the rear end of the frame over which the bottom run of the belt passes for guiding it to the rear pulley, and power means adjustably supported by and above the frame for driving the belt.

30 9. A portable conveyor, comprising a hollow wheeled frame with a trough extending longitudinally at the top thereof, an endless belt having its upper run in the trough and its lower run below the trough, the frame being supported by wheels adjacent the rear end thereof, the frame being angularly reduced in height at the bottom from a point adjacent the mounting wheels to the rear end thereof so the front end can be raised to a greater height, a driving pulley mounted at the front end of the frame over which the belt passes, a belt tensioning pulley mounted at the rear end of the frame over which the belt passes, an idler pulley mounted within the frame below the trough adjacent the rear end of the frame over which the lower run of the belt passes to guide this portion of the belt in the inclined portion of the frame to the rear pulley thereof, and power means mounted in the frame and having a driving connection with the front pulley for driving the belt.

35 10. In a conveyor, the combination with an elongated hollow frame having an open trough at the upper side thereof, of means mounting the frame for variably inclining it endwise, a continuous belt having its upper run movable in the trough and its lower run in the frame below the trough, a driving pulley at the front end of the frame, an adjustable pulley for the belt at the rear end of the frame, an adjustable engine support carried by the frame and overlying the trough intermediate the ends thereof, an engine mounted on the support, a speed reducing drive connected to the pulley at the front end of the frame and comprising a second driving pulley extending outwardly from the frame adjacent the engine, and a driving pulley connected to the engine and extending outwardly from the frame pending upon the inclination thereof, a driving pulley, a driving belt extending between the engine driving and said second driving pulleys, and an idler pulley mounted upon a weighted lever for engaging the driving belt between the two last said pulleys for keeping the belt tight independent of the inclination of the conveyor,

said lever being pivotally mounted on said support.

11. A conveyor, comprising a frame mounted for variable endwise inclination having a belt moving longitudinally thereof, a driving pulley mounted in the frame at the front end of the belt, a tightening pulley adjustably mounted in the frame at the rear end of the belt, a pair of motor mounting plates extending upwardly at the sides of the frame, a motor mounted in the plates and means for holding it in various angular positions with respect to the plates depending upon the inclination thereof, a driving pulley extending from one end of the motor at the side of the frame, a reduction drive connection mounted in the frame connected with the pulley at the front end of the belt, and having a drive pulley adjacent the said motor driving pulley projecting at one side of the frame, a driving belt connection between the motor driving pulley and the drive pulley at the side of the frame, a belt tightener pulley for engaging the said driving belt connection, and a lever upon which the belt tightener pulley is mounted pivoted to the adjacent side plate and having a long weighted free end which holds the idler.

8
pulley in engagement with the side driving belt connection.
